US00D906968S

(12) **United States Design Patent** (10) **Patent No.:** **US D906,968 S**
(45) **Date of Patent:** **** Jan. 5, 2021**

(54) **MOTOR FOR ELECTRIC POWER UNIT**

(71) Applicant: **HONDA MOTOR CO., LTD.**, Tokyo (JP)

(72) Inventor: **Koichi Azuma**, Wako (JP)

(73) Assignee: **HONDA MOTOR CO., LTD.**, Tokyo (JP)

(**) Term: **15 Years**

(21) Appl. No.: **29/702,853**

(22) Filed: **Aug. 22, 2019**

(30) **Foreign Application Priority Data**

Feb. 27, 2019 (JP) 2019-003970

(51) **LOC (13) Cl.** **13-02**

(52) **U.S. Cl.**

USPC **D13/122**; D23/412

(57) **CLAIM**

The ornamental design for a motor for electric power unit, as shown and described.

DESCRIPTION

FIG. 1 is a top, front, right side perspective view of a motor for electric power unit, showing my new design; FIG. 2 is a top, front, left side perspective view thereof; FIG. 3 is a top, rear, right side perspective view thereof; FIG. 4 is a top, rear, left side perspective view thereof; FIG. 5 is a front elevation view thereof; FIG. 6 is a rear elevation view thereof; FIG. 7 is a right side elevation view thereof; FIG. 8 is a left side elevation view thereof; FIG. 9 is a top plan view thereof;

FIG. 10 is a bottom plan view thereof; and,

FIG. 11 is a top, front, right side perspective view of the motor for electric power unit of FIG. 1, shown at a reduced scale and in a condition of use.

The broken lines in the drawings depict portions of the motor for electric power unit that form no part of the claimed design.

1 Claim, 11 Drawing Sheets
